(57) **CLAIM**

The ornamental design for a portion of a vehicle for work machine, as shown and described.

DESCRIPTION

FIG. 1 is a left side view of a portion of a vehicle for work machine showing our new design;

FIG. 2 is a right side view thereof;

FIG. 3 is a front view thereof;

FIG. 4 is a top view thereof;

FIG. 5 is an upper left front perspective view thereof;

FIG. 6 is an upper right rear perspective view thereof;

FIG. 7 is an enlarged top view thereof; and,

FIG. 8 is an enlarged upper left rear perspective view thereof. A bottom view is omitted because it is plain and unornamental and forms no part of the subject matter of the claimed design.

The broken line showings of FIGS. 1-8 are environmental only and not part of the claimed design.

The dashed-dotted line showings of FIGS. 3-5, and 7 illustrate a boundary between the claimed design and environmental features.
